UNITED STATES PATENT OFFICE.

RICHARD M. BOLTON, OF CHICAGO, ILLINOIS.

GAS-DISPENSING DEVICE.

1,158,780.

Specification of Letters Patent.

Patented Nov. 2, 1915.

Application filed April 9, 1914. Serial No. 830,686.

To all whom it may concern:

Be it known that I, RICHARD M. BOLTON, a citizen of the United States, and a resident of the city of Chicago, county of Cook, and 5 State of Illinois, have invented certain new and useful Improvements in Gas-Dispensing Devices, of which the following is a specification.

My invention relates to means for administering gases and the like for medical purposes and the object of my improvement is the production of a simple and effective device of the character mentioned which is particularly adapted for use in administering 10 gases to patients in dentistry for producing analgesia and anesthesia.

Other objects will appear hereinafter.

The invention consists in the combinations and arrangements of parts hereinafter described and claimed.

The invention will be best understood by reference to the accompanying drawing forming a part of this specification, and in which

25 Figure 1 is a view, in perspective, illustrating the application of a device which embodies my invention, for administering gases for medicinal purposes, Fig. 2 is an enlarged front view of the device showing 30 the securing band and one of the feeding tubes broken away and the other feeding tube entirely removed, and Fig. 3 is a central vertical section of the device.

The preferred form of construction as illustrated 35 in the drawing comprises a hollow body 4 having its rear side open and such rear side shaped to fit over the nose of a patient in order to restrict the passage of air into or out of said body. A cushion 5 is secured 40 around the opening in the rear of body 4 and is adapted to form a substantially air tight joint between the face of a person and the body 4. The cushion 5 may be so shaped that it will be held to the body 4 by friction or it may be secured with a suitable adhesive, such as glue.

Near the upper ends of the lateral walls of the body 4 are openings 6 adapted for the passage of the gases to be used into the device. On the lateral walls of body 4 are provided nipples 7 which are preferably formed integral with said walls and adapted to receive the ends of flexible tubes 8. The tubes 8 may be of soft rubber or any other suitable 55 substance. As indicated in Fig. 1 the tubes 8 are brought together at a convenient dis-

tance from the device and engaged on a Y-connection 9. The connection 9 is connected to a source of gas supply, not shown, by means of tube 10.

A discharge opening is formed in the lower side of the front wall 11 of body 4 and substantially on a line with the nostrils of a patient when the device is in operative condition in order to form as straight and short a passage from the nostrils as possible. In the opening in the wall 11 is threaded a hollow plug 12 having a shoulder 13 adapted to engage a plate 14 which is disposed across the front of the body 4. The arrangement 70 is such that the plug 12 is threaded in the opening in wall 11 and securely binds plate 14 in position. On the outer side of plug 12 is provided a flap valve 15 secured to the plug 12 by means of a screw 16, or its equivalent.

At each end of plate 14 is an eye 17 and in each eye is the end of a flexible band 18. Said flexible band is adapted to pass around the head of a patient in order to maintain 80 the device in operative condition.

In operation the device is applied to the face of a patient substantially as indicated in Fig. 1 and pipe 10 connected with a suitable source of gas supply (not shown). The 85 gas in passing through openings 6 enters the upper portion of the chamber in body 4 and passes around the nose of a patient to his nostrils. In exhaling the flap valve 15 is flexed outwardly permitting the patient's 90 breath to escape through the perforation of plug 12. As soon as the patient is through exhaling and begins to inhale, the gas is drawn through openings 6 again and this 95 operation continued during use of the device. A further reason for placing the openings 6 high up in the body 4 is to permit the positioning of tubes 8 away from the mouth of the patient and to take them away from the head and neck of the patient. This permits the dentist to have free access to the 100 mouth of the patient.

While I have illustrated and described the preferred form of construction for carrying my invention into effect, this is capable of 105 variation and modification without departing from the spirit of the invention. I, therefore, do not wish to be limited to the precise details of construction set forth, but desire to avail myself of such variations and 110 modifications as come within the scope of the appended claim.

Having described my invention what I claim as new and desire to secure by Letters Patent is:

A device of the class described, comprising a hollow body having an open side and adapted to fit over the nose of a person, inlet openings in the side walls of said body adjacent the upper end of the device, there being a discharge opening in the front wall lower than said inlet openings and above the bot-

tom wall, and a flap valve normally closing the said discharge opening substantially as described.

In testimony whereof I have signed my name to this specification in the presence of 15 two subscribing witnesses.

RICHARD M. BOLTON.
